(57) **CLAIM**

The ornamental design for a wallet, as shown and described.

DESCRIPTION

3. Wallet

Fig. 3 is a perspective view of a wallet. The portion of the wallet shown in solid lines in the drawing is intended to hold a round GPS tracker.

The evenly spaced dashed lines show stitching that form part of the design.

The dot-dashed lines show the boundary lines and form no part of the claim.

The un-shaded central portion does not form part of the claim.
